[57] CLAIM

The ornamental design for a carrying handle for caskets and the like, as shown and described.

DESCRIPTION

FIG. 1 is a top perspective view of a carrying handle for caskets and the like showing my new design; FIG. 2 is a bottom perspective view thereof; FIG. 3 is a front elevational view thereof, the rear view being a mirror image;

FIG. 4 is a top plan view thereof;

FIG. 5 is a bottom view thereof;

FIG. 6 is a left side elevational view thereof;

FIG. 7 is a right side elevational view thereof;

FIG. 8 is a sectional view taken along line 8—8 of FIG. 3; and,

FIG. 9 is a perspective view thereof, the broken line portions being for illustrative purposes only and forming no part of the claimed design.
